UNITED STATES PATENT OFFICE.

JOHN D. BALDWIN, OF PHILADELPHIA, PENNSYLVANIA, ASSIGNOR TO JOHN & JAMES DOBSON, OF SAME PLACE.

DESIGN FOR CARPET.

Specification forming part of Design No. 11,442, dated September 30, 1879; application filed August 1, 1879.
[Term of patent 3½ years.]

To all whom it may concern:

Be it known that I, JOHN D. BALDWIN, of the city and county of Philadelphia, State of Pennsylvania, have invented a certain new and Improved Design for Carpets.

The nature of my design is fully set forth in the accompanying photographic illustration, to which reference is made.

What I claim as my invention, and desire to secure by Letters Patent, is—
The design for carpet, as shown.

JOHN D. BALDWIN.
